UNITED STATES PATENT OFFICE.

JOSEPH J. SHIPLEY, OF WASHINGTON, DISTRICT OF COLUMBIA.

VENDING-MACHINE.

1,115,599.

Specification of Letters Patent. Patented Nov. 3, 1914.

Application filed September 18, 1913. Serial No. 790,660.

To all whom it may concern:

Be it known that I, JOSEPH J. SHIPLEY, a citizen of the United States, residing at Washington, District of Columbia, have invented certain new and useful Improvements in Vending-Machines, of which the following is a specification.

The invention relates generally to vending-machines, but more particularly to machines for vending newspapers, periodicals, magazines, and similar articles; and it has for its principal object to provide a device by which a person, upon the deposit of a proper coin, may obtain the desired article.

A further object of the invention is to simplify and cheapen the cost of construction of the several mechanisms for accomplishing the delivery of the article for which the proper coin has been deposited.

The invention consists in providing a suitable container for the articles to be vended, and novelly-constructed mechanisms for locking and unlocking a delivery slide, and for delivering the article.

The invention further consists in the general arrangement and combination of the several mechanisms, as will be hereinafter fully described in this specification, and briefly stated in the claims.

In the drawings—Figure 1 is a central, longitudinal section of my improved newspaper vending machine; Fig. 2, a side elevation of the locking and unlocking-mechanism, the full lines showing the parts in locked position, and the dotted lines showing them in unlocked position; Fig. 3 a horizontal section on line 3—3 of Fig. 2; Fig. 4, an enlarged view of the operating mechanism and a portion of the casing, and Fig. 5 a vertical section on line 5—5 of Fig. 4.

Referring to the several views, the numeral 1 indicates a casing constructed of any suitable material, preferably sheet steel stamped out. Each inner side wall, near the bottom, is provided with a groove 2, and slidable in said groove is a slide 3 upon which the articles to be vended are placed, said slide having its rear end provided with slots into which extend stops 4, 4, arranged upon the bottom of the casing to support the ends of the papers, or other articles. The rear end of the slide, between the stops, is provided with a vertically adjustable, right angle plate 5, for engaging the rear end of the lower article resting upon the

slide, and carry it forward as said slide is drawn out, the angle plate being adjusted by the set-screw 6. The forward end of the slide projects through a transverse, horizontal slot or opening 7 in the front end of the casing, and is provided with a hand-hold 7', an adjustable plate 8 being arranged above the opening, so as to narrow or widen the opening, according to the thickness of the article to be vended.

Attached to the slide, at one side thereof, is a slotted locking-plate 9, the front end of the slot inclines downwardly and terminates in a vertical slot 10. Projecting through a slightly curved slot 11 in the side wall of the casing, near the vertical slot 10, is a locking stud 12 carried by a locking-lever 13, which is pivoted on a short arm 14 attached to the outer side of said wall. The free or forward end of the locking-lever passes through a slot 15, in a partition 16, as shown by dotted lines in Fig. 3 and by full lines Fig. 5, and pivoted on said lever is a tilting-coin plate 17. Hinged to the partition 16, directly above the coin-plate is an interceptor 18 for intercepting the deposited coin. The interceptor is provided with a short arm 19 which passes through a slot 20 in the partition 16, and to said arm is attached a counterbalance 21, provided with a slot or loop 22 through which the locking-lever passes, the slot or loop being of a length sufficient to limit the distance the interceptor will be permitted to drop or tilt to allow the coin to be dropped upon the coin-plate 17. Arranged on the locking-lever is a counterbalance 23 capable of being adjusted thereon so as to be overcome by the weight of the proper coin, whether it be a penny, a nickel, or a dime.

The coin-actuating mechanism is inclosed in a suitable casing 24, in which is provided a coin-chute 25, in the top of which is an orifice 26 for the reception of the coin. The casing is also provided with a coin-compartment 27 for the reception of the deposited coins, and is provided with a door 28 for access to the coin-compartment, the door being provided with a suitable lock.

In operation, the articles to be vended—in the present instance, newspapers—are placed within the casing upon the slide, and a suitable follower not shown, is placed thereon to facilitate the delivery of the article. The proper coin being dropped through the orifice, falls upon the interceptor, and

overcoming the counterbalance 21, drops upon the coin-plate; the weight of the coin depresses the forward end of the locking-lever, raising the locking-stud 12 out of locking-engagement with the slot 10 of said locking-plate, setting the slide free to be pulled out. As the slide is being pulled out the locking-stud is caused to ride up the lower edge of the downwardly-inclined 10 tension of the slot 10, and further raise the inner or rear end of the locking-lever, and further depress its forward end carrying the coin-plate, which action causes the rear end of said coin-plate to ride upon a wire 29 15 extending beneath the coin-plate, as the slide is drawn out, and drop the coin into the coin-compartment, the tilting movement of the coin-plate being limited by a pin 30, as clearly shown in Fig. 4. This further or 20 extended movement of the locking-lever resets the interceptor 18, so that if the next purchaser should drop in a coin while the slide is in its out-position, the coin will not drop onto the coin-plate, as the locking-lever, being at the lower end of the slot 22 of the counterbalance, will hold the interceptor in its reset position, and by pushing in the slide the purchaser will obtain his paper, as the coin will then fall upon the 25 coin-plate and cause the disengagement of the locking-stud from the locking-slot 10, as hereinbefore described. By pivoting the coin-plate on the end of the locking-lever and arranging the wire 29 beneath the rear 30 end of the coin-plate so as to cause said coin-plate to tilt quickly, the downward or tilting movement of the locking-lever is greatly shortened and this constitutes an important feature of my invention.

40 Various modifications in the detailed construction of the various parts of the coin-actuating mechanism may be made without departing from the spirit of my invention or sacrificing the principle thereof, such, 45 for instance, as making the rails on the slide instead of on the side walls of the casing, and the grooves in the side-walls.

Having thus fully described my said invention, what I claim is:—

50 1. A vending-machine having in combination, a movable slide upon which the vendible articles are placed, a slotted locking-plate carried by the slide, a pivoted lock-

ing-lever carrying a pivoted coin-plate, a hinged coin interceptor situated above the coin-plate, and means connected with the locking lever for resetting the interceptor.

2. A vending-machine having in combination, a movable slide upon which the vendible articles are placed, a locking-plate 60 provided with straight slot terminating in an inclined and vertical slot, a pivoted locking lever having a lug adapted to enter the vertical slot, a coin-plate pivoted on the locking-lever, means for quickening the tilting action of the coin plate, an interceptor hinged above the coin-plate, and a connection between the interceptor and locking-lever, whereby the interceptor is reset.

3. A vending-machine having in combination, a movable slide provided with a slotted locking-plate, a pivoted locking-lever arranged to lock the slide until the proper coin has been deposited, a coin-plate pivoted on the locking-lever, a coin-interceptor, and 75 a counterbalance loosely connecting said locking lever with said interceptor for resetting the interceptor.

4. A vending machine having in combination, a movable slide provided with a slotted locking-plate, a pivoted locking-lever arranged to lock the slide until the proper coin is deposited, a coin-plate pivoted on the locking-lever, a wire arranged below said locking-lever so as to quicken the tilting- 85 action of the same, a coin-interceptor, and a slotted counterbalance loosely connecting the locking-lever with said interceptor, whereby the latter is reset.

5. A vending machine having in combination, a movable slide provided with a slotted locking-plate, a pivoted locking-lever, a coin-plate pivoted on the locking-lever, a coin-interceptor situated above the coin-plate, a connection between the interceptor 95 and coin-plate for resetting the interceptor, and means for quickening the tilting action of the coin-plate independent of the movement of the locking-lever.

In testimony whereof I affix my signature 100 in presence of two witnesses.

JOSEPH J. SHIPLEY.
